UNITED STATES PATENT OFFICE

162,487

TRAWL NET SLED

Oscar M. Sorensen, Fernandina, Fla.

Application May 25, 1950, Serial No. 10,166

Term of patent 14 years

(Cl. D31—4)

To all whom it may concern:

Be it known that I, Oscar M. Sorensen, a citizen of the United States, residing at Fernandina, in the county of Nassau and State of Florida, have invented a new, original, and ornamental Design for a Trawl Net Sled, of which the following is a specification, reference being had to the accompanying drawing, forming part thereof.

Figure 1 is a side elevational view of a trawl net sled, showing my new design.

Figure 2 is a top plan view of the same.

Figure 3 is a front end elevation.

Figure 4 is a rear end elevation.

I claim:

The ornamental design for a trawl net sled, as shown.

OSCAR M. SORENSEN.
